US0D1099046S

(12) **United States Design Patent** (10) **Patent No.:** **US D1,099,046 S**
(45) **Date of Patent:** **** Oct. 21, 2025**

(54) **CIRCUIT BREAKER**

(71) Applicant: **LS ELECTRIC CO., LTD.**, Anyang-si (KR)

(72) Inventor: **Minho Choi**, Gyeonggi-do (KR)

(73) Assignee: **LS ELECTRIC CO., LTD.**, Anyang-si (KR)

(**) Term: **15 Years**

(21) Appl. No.: **35/521,673**

(22) Filed: **Jun. 25, 2024**

(80) **Hague Agreement Data**

Int. Filing Date: **Jun. 25, 2024**

Int. Reg. No.: **DM/238380**

Int. Reg. Date: **Jun. 25, 2024**

Int. Reg. Pub. Date: **Jul. 19, 2024**

(30) **Foreign Application Priority Data**

Jan. 4, 2024 (KR) 30-2024-0000509
